UNITED STATES PATENT OFFICE.

NELSON J. WARREN AND WILLARD C. SMITH, OF SIOUX CITY, IOWA.

OIL BURNER.

Application filed May 14, 1921. Serial No. 469,447.

To all whom it may concern:

Be it known that we, NELSON J. WARREN and WILLARD C. SMITH, citizens of the United States, and residents of Sioux City, in the county of Woodbury and State of Iowa, have invented certain new and useful Improvements in Oil Burners, of which the following is a specification.

Our invention contemplates an improved oil burner, embodying certain novel features of construction and arrangement of parts which facilitate vaporization of the fuel.

Another object of the invention is the production of a fuel burner, embodying novel characteristics which reduce carbon accumulation to the minimum.

Still another object of the invention is the production of an oil burner, embodying an improved jet which may be readily taken apart and assembled for the purpose of cleaning.

Furthermore, the invention contemplates an oil burner having a jet provided with an adjustable opening.

With these and other objects in view the invention will be clearly understood from the following description, reference being had to the accompanying drawings, of which:

Fig. 1 is an elevation of a device constructed in accordance with the invention, parts being cut away and shown in section, and

Fig. 2 is a plan of the adjustable jet cap.

Referring to the illustration, 1 represents a suitable generating pan, adapted to be supported by the usual furnace grates, or otherwise. Above the said pan is mounted a U-shaped duct, comprising arms, 2 and 3, and a web, 4, interconnecting the lower ends of the arms. From the arm, 2, adjacent the web, 4, depends an induction tube, 5, which may be formed integrally with the U-shaped duct and is adapted to communicate with a suitable source of oil supply. The upper ends of the arms, 2 and 3, are interconnected by, and communicate with, an enlarged chamber, 6, in which the oil is vaporized and expanded.

The web, 4, is provided with a vertical, transverse opening, 7, through which projects a cylindrical nozzle, 8, threaded into the opening, 7, as at 9, and projecting a distance therethrough, and having on its lower end a shoulder, 10, between which and the web, 4, may be interposed packing, 13. The

nozzle is provided with an axial opening, 12, and a lateral induction opening, 15, communicating with the opening, 12, and the tubular arm, 3. On the upper end of the nozzle is a cap, 14, rotatable around an upwardly-projecting stem, 16, on the nozzle and disposed coaxially therewith, the cap being held in engagement with the nozzle by a suitable compression-spring, 25, interposed between a cross pin, 24, through the stem, and the cap, 14. The cap is provided with a circular series of differently-sized openings, 26, arranged concentrically with the stem, and separately registerable with an opening, 28, in the nozzle, disposed eccentrically to the stem and communicating with the opening, 12.

We provide a cleaning device for the jet, preferably including a packing gland, 17, adapted to be carried by a suitable support below the plane of the pan, 1, as by threading the gland through a wall, 18, of the furnace. The gland slidably encloses a pushrod, 19, connected with a flexible element, as 20, a wire, 20, slidably-enclosed in a guide tube, 21, secured at one end to the gland, 17, and at the other end to the nozzle, the wire being extended into the nozzle and adapted to be projected through the nozzle opening, 28, and one of the cap openings, 26, to clean the carbon therefrom, through the medium of the pushrod, 19. The wire, 20, is held normally retracted from the said opening, as by a compression-spring, 22, interposed between the packing gland and a head, 23, on the end of the pushrod. The lower ends of the cap openings, 26, are preferably conical or counter-sunk, as at 27, to facilitate entrance of the cleaning wire.

In generating the burner a quantity of oil is admitted to the pan from the jet and then ignited to sufficiently vaporize the fuel within the chamber, 6, and arms, 2 and 3, to cause ignition of the fuel at the jet; and the jet, being positioned directly below the chamber, 6, the latter is kept intensely hot, whereby the fuel is vaporized and expanded. The chamber, 6, being cylindrical and its bottom flat, serves to deflect and spread the flame from the jet radially in all directions.

Obviously, by rotating the cap, 14, any chosen size of the openings, 26, may be placed in registration with the nozzle opening, 28.

Having thus described our invention, what we claim as new and desire to secure

21 by Letters Patent of the United States; is:

1. An oil burner embodying a substantially U-shaped member including tubular arms, and a web part interconnecting the same, a vaporizing chamber interconnecting and communicating with the upper ends of the arms, an induction passage communicating with one of said arms, the web having a vertical opening, and a nozzle extending through and removably secured in said opening and having a lateral opening communicating with the other of said arms.

2. A burner including a nozzle having an induction opening, and a member rotatable on the end of the nozzle, the nozzle having an end opening communicating with the induction opening and positioned a distance from the axis of rotation of said member, and said member having a circular series of different sized openings concentric with the axis of rotation of said member, the latter openings being so arranged that any chosen one thereof may be placed in registration with said end opening by rotation of said member.

3. A burner including a nozzle having an induction opening and a cylindrical end portion having an eccentric opening communicating with the induction opening; an axial stem projecting from said end; a plate rotatable on the stem and having a circular series of openings arranged concentrically with the stem, whereby any chosen opening of the series may be placed in registration with the eccentric opening by rotation of the plate; a lateral projection on the stem, and a compression spring between the projection and plate to hold the plate against the nozzle.

4. A burner including a tubular fuel passage having a transverse opening therethrough; a cylindrical nozzle projecting through the opening and threaded into the

tube, having a lateral opening communicating with the passage and an end opening communicating therewith and positioned eccentrically to the nozzle, an axial stem on the nozzle, a cap on the nozzle rotatable on the stem and provided with a circular series of openings concentric with the stem, whereby any chosen one of the latter openings may be placed in registration with said eccentric opening, a lateral projection on the stem; and a compression spring between the cap and projection to hold the cap against the nozzle end.

5. A burner including a cylindrical nozzle having an opening in one end thereof, and an eccentric opening in the other end thereof, a plate rotatable on the latter end and having a circular series of openings therethrough, any chosen one of which may be placed in registration with said eccentric opening by rotation of the plate, and a wire extending into said first opening and adapted to be extended through the eccentric opening and any of said plate openings registering therewith.

6. A burner including a cylindrical nozzle having an opening in one end thereof, and an eccentric opening in the other end thereof; a plate rotatable on the latter end and having a circular series of openings therethrough, any chosen one of which may be placed in registration with said eccentric opening by rotation of the plate; a tube secured to said first end and bent at an angle thereto, and a flexible element slidable in the tube to extend through said eccentric opening, and any of said plate openings registering therewith.

In testimony whereof, we have hereunto set our hands this 28th day of April, 1921.

NELSON J. WARREN,
WILLARD C. SMITH.
